(57) **CLAIM**

(21) Appl. No.: **29/140,698**

An ornamental design for a glazing bead extrusion, as shown
and described.

(22) Filed: **Apr. 23, 2001**

DESCRIPTION

(51) LOC (7) Cl. **25-01**
(52) U.S. Cl. **D25/119**
(58) **Field of Search** D25/124, 119,
D25/52, 60; 52/730.3, 656.6, 204.5, 204.56,
204.51, 730, 205.1, 202; 49/501, 504, DIG. 2,
404, 413, 419, 407, 408

FIG. 1 is a perspective of the glazing bead extrusion
showing my new design the glazing bead extrusion being of
indefinite length; and,

FIG. 2 is an end elevational view of the glazing bead
extrusion of FIG. 1.
